UNITED STATES PATENT OFFICE.

WILLIAM McNAMARA, OF BOSTON, MASSACHUSETTS.

FAN.

SPECIFICATION forming part of Letters Patent No. 710,295, dated September 30, 1902.

Application filed March 19, 1902. Serial No. 98,906. (No model.)

To all whom it may concern:

Be it known that I, WILLIAM McNAMARA, a citizen of the United States, residing at Boston, in the county of Suffolk and State of Massachusetts, have invented certain new and useful Improvements in Fans; and I do hereby declare the following to be a full, clear, and exact description of the invention, such as will enable others skilled in the art to which it appertains to make and use the same.

This invention relates to fans; and it consists in the novel construction of the same, as hereinafter fully described and claimed.

15 In the drawings, Figure 1 is a front view of the fan. Fig. 2 is a side view of the fan.

A is the blade of the fan, which is of any desired shape, but preferably of a shape similar to an ordinary palm-leaf fan.

20 B is the shank of the fan, which is formed integral with it, the whole being stamped or cut out of a thin metallic plate. Any approved metal, such as steel, may be used; but a metal having considerable elasticity is preferred.

C is a handle which is formed of wood or other convenient material and secured to the shank B in any approved manner.

D represents flanges or beads formed on 30 the sides of the shank between the handle and the blade by turning over the metal of the shank and lower part of the blade. These flanges operate to make the fan-shank stiffer and constrain the fan-blade to bend across

the dotted line x when it is vibrated with 35 considerable force.

Advertising matter may be stamped, printed on, or secured to one or both sides of the fan-blade.

The fan is used in the ordinary manner to 40 produce a current of air; but when used violently the fan-blade bends across the line x and makes a great noise. This fan is intended for use in political meetings, processions, and other gatherings which are sometimes heated and in which the production of considerable noise is sometimes effective 45 and desirable.

What I claim is—

1. A fan formed of a thin sheet of resilient 50 material and provided with stiffening portions or beads at its lower side portions which constrain the fan to bend at a prearranged line when used violently, substantially as set forth.

2. A fan formed of a thin sheet of metal and having a shank which is formed integral with its blade and provided with stiffening flanges or beads which constrain the fan-blade to bend when used violently on a line 60 above the top of the shank, substantially as set forth.

In testimony whereof I affix my signature in presence of two witnesses.

WILLIAM McNAMARA.
